UNITED STATES PATENT OFFICE

JOHN I. McCOY, OF PITTSBURG, PENNSYLVANIA, ASSIGNOR OF ONE-HALF
TO HARRY HAMILTON, OF PITTSBURG, PENNSYLVANIA.

CURTAIN HANGER OR SUPPORT.

No. 852,894.

Specification of Letters Patent.

Patented May 7, 1907.

Application filed November 19, 1906. Serial No. 344,171.

To all whom it may concern:

Be it known that I, JOHN I. McCOY, a citizen of the United States, residing at Pittsburgh, in the county of Allegheny and State of Pennsylvania, have invented certain new and useful Improvements in Curtain Hangers or Supports, of which the following is a specification.

The object of my invention is to provide
10 an improved curtain hanger or support which
may be swung down into such a position that
a person standing on the floor may drape the
curtain upon the pole and which may be
readily swung up to operative position after
15 the curtain has been draped, and a further
object of the invention is to provide an im-
proved construction of curtain support or
hanger of this character which may be read-
ily extended both laterally and longitudi-
20 nally so as to accommodate the device for
windows of different sizes.

With this and other objects in view as will
more fully appear as the description proceeds,
the invention consists in certain construc-
25 tions, and arrangements of the parts herein-
after described and particularly pointed out
in the appended claims.

For a full understanding of the invention
and the merits thereof and also to acquire a.
30 knowledge of the details of construction of
the means for effecting the result, reference is
to be had to the following description and ac-
companying drawings, in which:

Figure 1 is a face view of the window hav-
35 ing our improved curtain hanger or support
applied thereto and with the device shown in
elevated position; Fig. 2 is a side elevation
with the curtain support lowered; Fig. 3 is a
detail perspective view of the sectional cross
40 bar of the device with its clamping sleeve;
and, Fig. 4 is a detail perspective view of one
of the extensible standards.

Corresponding and like parts are referred
to in the following description and indicated
45 in all the views of the drawings by the same
reference characters.

Referring to the drawings, the numeral 1
designates the side sills of a window frame to
which my improved device is applied, and 2
50 designates the two swinging standards of my
device which are constructed in sections 3
and 4 designed to overlap each other and
each provided with a yoke plate 5 extending

around the other section, so that the two sec-
tions are adapted to slide longitudinally, one 55
upon the other so that the standards may be
extended or retracted in length. One sec-
tion of each standard is secured by means of
a hinge 6 to one of the side bars of the win-
dow frame, at the desired elevation. Set 60
screws 7 are provided to hold the two sections
of each standard at the desired adjusted ex-
tensions.

The two standards 2 are connected to-
gether at their free ends by means of a cross 65
bar 8 which is preferably mortised in one
of the sections of the standards and secured
thereto by screws or similar fastening de-
vices, and said cross bar is also constructed
in sections 9 and 10, as shown, the sections 70
extending toward each other and in aline-
ment therewith, and the inwardly extending
ends of the two sections 9 and 10 are mounted
to slide in a sleeve 11 common to both.
Set screws 12 are mounted in the sleeve 11 75
and are adapted to impinge against the sec-
tions 9 and 10 of the cross bar so as to hold
the section in the desired distance across
the window frame.

By the means above described, the swing- 80
ing frame constituted by the standards 2 and
the cross bar 8 may be extended both longi-
tudinally and laterally according to the size
of the window to which the device is to be ap-
plied. 85

Shade or curtain brackets 13 are secured
to the free ends of the respective swinging
standards 2 and project outwardly there-
from and are arranged to support the curtain
pole 14. Screw eyes or similar attaching de- 90
vices 15 are secured to the respective stand-
ards at the free ends of the same and chains
16 or similar flexible members are secured at
one end to the respective screw eyes and at
their other ends to any convenient portion of 95
the window frame so as to limit the down-
wardly and outwardly swinging movement
of the standards.

From the foregoing description in connec- 100
tion with the accompanying drawings, it will
be understood that whenever it is desired to
drape a curtain upon a pole, the standards 2
with their cross bars 8 are swung outwardly
and downwardly in convenient relation to 105
the floor, being held in such position by the
said flexible members and then a person may

readily drape a curtain over the pole without the necessity of using a chair or step-ladder for this purpose.

- To raise the device after the curtain has been draped on the pole and to maintain the device in its normal elevated position, the sleeve 11 that connects the two sections of the cross bar 8 is provided with a forwardly extending apertured ear 17 to which one end of the cord or cable 18 is secured, and said cable extends over a sheave or pulley 19 at the top of the window frame, and preferably over another pulley 20 located at one upper corner of the window frame and thence downwardly into convenient position to be operated from the floor. This actuating cord 18 may be secured by a cleat or the like, not shown, so as to maintain the device in its normal elevated position.
- As shown best in Fig. 3, I may secure to the sections 9 and 10 of the cross bar, the ordinary brackets that are designed to support a spring shade roller, such as that known as the Hartshorn type. To accomplish this result, I preferably employ two pairs of arms 21 that are mortised as indicated at 2 and are designed to fit the sections 9 and 10, as shown, and to embrace and be clamped to said sections by means of tie bolts 23. The ordinary brackets 24, above referred to, may be attached to the front arm of each pair, as shown in the drawings, by means of screws or any desired fastening means.

Having thus described the invention, what is claimed as new is:

An adjustable curtain support, comprising standards each of which is constructed in overlapping extensible sections, means for holding said sections at different extensions, said standards being adapted to be hinged at one end to the side bars of a window frame, curtain brackets secured to the free ends of said standards, a cross bar constructed in extensible sections which are connected to the standards, respectively, a connecting sleeve encircling the inner ends of both sections of the cross bar, set screws mounted in said connecting sleeve and adapted to impinge against the respective sections of the cross bar, said sleeve being provided with an apertured ear, a cord secured at one end of said ear and adapted to pull the cross bar upwardly, and flexible limiting members connected at one end to the free ends of the standards and at their upper ends to the window frame and designed to limit the outwardly and downwardly swinging movement of the standards, as and for the purpose set forth.

In testimony whereof I affix my signature in presence of two witnesses.

JOHN I. MCCOY. [L. s.]

Witnesses:

C. F. GREATHAUSER,
M. H. ENGLAND.
